Primary Examiner — Rosemary K Tarcza*Assistant Examiner* — Lacey Chey Bowman(74) *Attorney, Agent, or Firm* — Dragon Sun Law Firm, PC; Jinggao Li, Esq.; Nathaniel Perkins(57) **CLAIM**

The ornamental design for a hunt camera, as shown and described.

DESCRIPTION

FIG. 1 is a perspective view of a hunt camera showing my new design;

FIG. 2 is another perspective view of FIG. 1

FIG. 3 is a front view of FIG. 1;

FIG. 4 is a rear view of FIG. 1;

FIG. 5 is a top view of FIG. 1;

FIG. 6 is a bottom view of FIG. 1;

FIG. 7 is a left view of FIG. 1; and,

FIG. 8 is a right view of FIG. 1.

The broken lines illustrate portions of the hunt camera that form no part of the claimed design.

1 Claim, 8 Drawing Sheets(56)
